UNITED STATES PATENT OFFICE.

HERBERT S. RENTON, OF BROOKLYN, NEW YORK, ASSIGNOR OF ONE-HALF
TO JACOB MANNESCHMIDT, JR., OF BROOKLYN, NEW YORK.

AIR-INLET VALVE.

SPECIFICATION forming part of Letters Patent No. 718,657, dated January 20, 1903.

Application filed August 4, 1902. Serial No. 118,228. (No model.)

To all whom it may concern:

Be it known that I, HERBERT S. RENTON, a citizen of the United States, residing in the borough of Brooklyn, in the county of Kings and State of New York, have invented certain new and useful Improvements in Air-Inlet Valves, of which the following is a specification, reference being had therein to the accompanying drawings.

10 My invention relates to air-inlet valves such as are employed for the air-inlets of soil or drain pipes or conduits of buildings for the purpose of admitting air to ventilate such pipes or conduits. It is desirable that such 15 valves shall afford free admission of air, but shall prevent the escape of air or gases from the pipe or conduit, and according to my invention the valve when in open position affords practically no obstruction to the passage to be ventilated, the open valve giving practically the full cross-sectional area of the interior of the passage in which the valve is located.

20 My invention also has for its objects simplicity of construction, durability, and reliability of action.

25 My invention includes various improvements in the construction of such valves.

I will now particularly describe the construction embodying my invention illustrated in the accompanying drawings, forming part hereof, and will thereafter point out my invention in claims.

30 Figure 1 is a longitudinal vertical section of a valve and casing embodying my invention. Fig. 2 is a transverse vertical section of the same, taken on a plane indicated by the line 2 2, Fig. 1. Fig. 3 is a perspective view of the valve and seat with the valve in 35 normal open position.

A return-bend inlet *a* is shown which constitutes the casing for the valve and is adapted to be connected at its end *a'* to a soil-pipe or other pipe or part to be ventilated and is 40 open to the atmosphere at its other end *a''*, and, as shown, a screen *b* is provided at the air end of the inlet to prevent tampering with the valve.

The casing is shown as provided with a cap 45 *c*, which is suitably removably clamped over a glass plate *d*, this glass plate being shielded

by gaskets *d'* above and below it and fitting into and covering an opening in the top of the casing, and this opening being located immediately above the valve, so as to permit 55 inspection of the valve through the glass plate *d* upon removal of the cap *c*.

The valve is carried by a frame *e*, in which is also formed the valve-seat, this frame being shaped to fit into an enlargement or 60 pocket *f*, formed in the casing, so that it may be dropped into such pocket and will be held therein by the cover, glass plate, and gaskets. This construction is exceedingly simple and permits the valve and frame to be inserted or 65 removed as a unit upon the removal of the cover *c* and glass plate *d*.

The valve is shown in the form of a flat plate, which may be of aluminium or other suitable material, with ears or lugs *j* bent or 70 struck up therefrom, these ears or lugs receiving a pivot-pin *h*, whereby the valve is pivoted at a point intermediate of its length. The frame *e* is shown as also provided with lugs *i* for the pivot-pin *h*, and the valve-seat 75 is on the inner face of the casing above the pivot-pin and on the outer face of the casing below the pivot-pin. The shoulders *e'*, formed by the tops of the lower part of the valve-seat, act as stops to limit the opening movement of the valve and determine the normal open position thereof. (Shown in broken lines in Fig. 1 and in full lines in Fig. 3.)

The frame *e* may be made of aluminium or other suitable material in a single piece or 85 casting, so as to be of light weight and practically incorrodible.

The pivotal axis of the valve is offset from the face of the valve, and the valve, by reason of the fact that its weight is disposed on 90 one side of its pivotal axis, tends always to move toward the open position, (shown in full lines in Fig. 3 and in broken lines in Fig. 1,) as thereby its center of gravity is moved to lowest position. The portion of the valve 95 above its pivotal axis is greater in area of surface than the portion of the valve below its pivotal axis, being shown as of greater length and also of larger area by reason of the fact that it is of rectangular outline, while 100 the portion of the valve below its pivotal axis is of circular outline, and the larger upper

portion is obviously of somewhat greater weight than the smaller lower portion, tending to hold the valve open. The tendency of the valve to remain open is counteracted to some extent and so as to produce a delicate poised of the valve with a normal tendency toward open position by an adjustable counterweight, shown as consisting of a nut *k*, threaded upon the rod *l*, this rod *l* projecting from the valve at the face of the valve which is uppermost when the valve is open. The arrangement and adjustability of this counterweight permits the counterbalance to be nicely adjusted, so that the valve will move under light pressure.

Under normal conditions the valve is open for the free admission of air to ventilate the drain or soil pipe or other part to which the valve is connected, and the tendency of any pressure upon the valve from incoming air, whether the valve is open or closed, is to open the valve, for the reason that the part of the valve opening inward—the upper part of the valve—is of larger area than the part of the valve opening outward—the lower part of the valve—and for the further reason that incoming currents of air are largely directed by the casing upwardly against the lower part of the valve and to some extent downwardly against the upper part of the valve. So long, therefore, as there is no appreciable circulation or movement of air within the casing the valve will remain open ready for the free admission of air, and the tendency of incoming air will always be to hold the valve open, so that the stronger the current of inflowing air the greater will be the force tending to hold the valve open. It will further be noted that with the valve open there is practically no obstruction to the inward movement of air, the open valve affording an opening of practically the full cross-sectional area of the interior of the casing. Should, however, the movement of air or gas within the casing be an outward movement, the valve will be at once closed, not only by reason of the fact that the outwardly-moving part of the valve is of the larger diameter, but also by reason of the fact that the casing will direct all outwardly-moving currents largely upwardly against the upper or outwardly-moving part of the valve and also to some extent downwardly against the lower or inwardly-moving part of the valve. Thus the valve will instantly close to prevent the outflow of air or gas from the soil-pipe and will remain closed so long as there is an outward pressure, preventing the escape of deleterious or ill-smelling-gases, and will open as soon as this pressure is removed and permit the free entrance of air to ventilate the soil-pipe.

While the return-bend construction of casing appears to be the most advantageous to the realization of the advantages of my invention, it is of course obvious that other forms of casing may be employed and that the construction and arrangement of the

valve may be modified within the spirit and scope of my invention.

What I claim, and desire to secure by Letters Patent, is—

1. An air-inlet device comprising a casing having an air-inlet opening and a valve-seat, and a valve pivoted on an axis intermediate of the length of its valve-faces and having a greater area in the portion of the valve which moves outwardly to close the valve than in the portion of the valve which moves inwardly to close the valve and having its weight disposed so that it will normally assume an open position and being so balanced in open normal position that the portion of greater area extends inwardly away from the air-inlet opening and the portion of lesser area extends outwardly toward the air-inlet opening, to provide in normal position of the valve an opening through the valve-seat which is practically free and unobstructed.

2. An air-inlet device comprising a casing and valve-seat, and a valve pivoted on an axis intermediate of its length and freely movable on such axis and having a greater area above its pivotal axis than below its pivotal axis, the part above its pivotal axis moving inwardly to open the valve and the part below its pivotal axis moving inwardly to close the valve, and having its weight disposed so that it will normally assume an open and approximately horizontal position but will be movable by light outward pressure to closed position.

3. An air-inlet device comprising a return-bend casing having an air-inlet opening and a valve-seat, and a valve located in the return-bend and pivoted on an axis intermediate of the length of the faces of the valve, and having a greater area in the portion of the valve which moves outwardly to close the valve than in the portion of the valve which moves inwardly to close the valve, and having its weight disposed so that it will normally assume an open position but will be movable by light outward pressure to closed position and being so balanced in open normal position that the portion of greater area extends inwardly away from the air-inlet opening and the portion of lesser area extends outwardly toward the air-inlet opening, to provide in normal position of the valve an opening through the valve-seat which is practically free and unobstructed.

4. An air-inlet valve in combination with a casing and valve-seat, the valve being pivoted on an axis intermediate of the length of the valve-faces and having a greater area in the portion of the valve which moves outwardly to close the valve than in the portion of the valve which moves inwardly to close the valve, and having an adjustable counterbalance on the part of the valve having the face of smaller area.

5. An air-inlet valve comprising the plate *g* with lugs *j* thereon, in combination with the frame *e*, having the valve-seat formed therein,

the pivot-pin *h*, passing through the lugs *j* and seated in the frame *e*, the frame *e* having shoulders *e'* to act as stops for the valve in open position, and a casing for the valve having a pocket adapted to receive the frame *e*, such casing having an opening to permit the insertion and removal of the frame and valve, and a removable cover for such opening, substantially as set forth.

10 6. In an air-inlet valve, the combination, with a casing and a frame in the casing having an approximately vertical valve-seat, of a pivot-pin extending transversely across the valve-seat at a point below its mid-length, the upper part of the valve-seat, above the pivot, being located at one side of the said frame and the lower part, below the pivot, being located at the other side of the frame, and a valve hung on said pivot and balanced in approximately horizontal position, the upwardly-closing portion of the valve being of greater area than the downwardly-closing portion and corresponding in size with the upper part of the valve-opening above the pivot, while the smaller portion corresponds in size with the lower part of the valve-opening.

7. In an air-inlet valve, the combination, with a casing provided with an approximately vertical guide pocket or groove, and a frame 30 guided in said pocket in the casing, said frame having a valve-seat, the upper portion of which is located at the opposite side of the said frame to the lower portion of the valve-seat, of a pivot extending transversely across 35 the valve-seat at a point between the said upper and lower portions of the valve-seat, the upper portion of the valve-opening being larger in area than the lower portion of the valve-opening, and a valve hung on said pivot 40 and balanced in approximately horizontal position transversely of the said guide-pocket, the upwardly-closing portion of the valve being of greater area than the downwardly-closing portion thereof, and corresponding in size 45 with the upper part of the valve-opening, while the smaller portion corresponds in size with the lower part of the valve-opening.

In testimony whereof I have affixed my signature in presence of two witnesses.

HERBERT S. RENTON.
